Primary Examiner — Sheryl Lane*Assistant Examiner* — Ieisha N Price(74) *Attorney, Agent, or Firm* — Oyen Wiggs Green & Mutala LLP(57) **CLAIM**

The ornamental design for a modular rail system connector, as shown and described.

DESCRIPTION

FIG. 1 is a bottom view of a modular rail system connector showing the new design;

FIG. 2 is a top view thereof;

FIG. 3 is a right-side view thereof, the left-side view being a mirror image thereof;

FIG. 4 is a rear view thereof;

FIG. 5 is a front, right-side, bottom perspective view thereof;

FIG. 6 is a front view thereof; and,

FIG. 7 is a top, rear, right-side perspective view thereof.

The broken lines in the drawings illustrate portions of the modular rail system connector and form no part of the claimed design.

1 Claim, 4 Drawing Sheets(56)
